UNITED STATES PATENT OFFICE.

MAX HERZBERG, OF NEW YORK, N. Y., ASSIGNOR TO EXCELLA PATTERN COMPANY, INC., OF NEW YORK, N. Y., A CORPORATION OF NEW YORK.

PATTERN AND PATTERN SET.

Application filed July 18, 1924. Serial No. 726,695.

To all whom it may concern:

Be it known that I, MAX HERZBERG, a citizen of the United States, residing at New York, in the county of New York and State of New York, have invented certain new and useful Improvements in Patterns and Pattern Sets, of which the following is a full, clear, and exact description, such as will enable others skilled in the art to which it appertains to make and use the same.

This invention relates to a pattern or pattern set such as is used by dressmakers, and aims to provide certain improvements over heretofore known devices of this character.

It is an object of the invention to furnish an improved pattern set, which will be of such a nature that the same may be utilized with facility by relatively inexperienced persons.

A further object is to be predicated on the provision of a set of patterns by the use of which garment portions are formed, which patterns will embody characteristics whereby the finished garment may be modified in certain particulars, the pattern set being furnished in such a manner that an operator will instantly know exactly how the pattern sections, and consequently, the garment portions, are to be arranged in order to produce perfect results.

A still further object is that of providing a pattern set which will preferably be of such a nature that an operator will be able to readily and properly correlate the various pattern sections.

Another object is that of furnishing an instruction-sheet preferably accompanying a set of pattern sections, which instruction-sheet will in certain respects furnish more explicit information than is incorporated in the pattern set.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed de-

scription taken in connection with the accompanying drawings, in which:

Fig. 1 shows a set of patterns such as are used to provide a finished garment;

Figs. 2, 3, 4 and 5 illustrate in detail certain of these pattern sections; and

Fig. 6 shows an instruction-sheet which preferably accompanies each set of patterns.

Referring particularly to Fig. 1 it will be noted that pattern sections 10 to 19 inclusive have been shown, and of these various sections, 10, 11, 12 and 16 have been illustrated in detail in Figs. 2, 3, 4 and 5, respectively.

It is preferred that each of the various sections be indicated in any desirable manner, as has, for example, been shown at 20, so that a person using the pattern will have no difficulty in determining the particular section upon which she is working, it being furthermore noted that, if desired, each pattern section may carry a trade mark indication 21.

In addition to the foregoing indicia each pattern section is conveniently provided with notches and perforations 22 and 23, respectively, and in the present embodiment of the invention the former are identified by reference characters as at 24, while the latter may also be identified by indicia in the nature of sets of instructions 25 and 26. Even though the characters 24 are utilized it is preferred that indicia in the nature of a set of instructions 27 be placed adjacent each of the same, so that, in addition to identifying each of the notches or similar portions by a character, specific instructions are provided in order that the pattern may be utilized with facility by a relatively untrained person.

In this connection it is of interest to note that in the present instance the instructions 27 do not alone refer to a general assembly operation, but specifically identify that pattern section which is to be arranged adjacent the section in use, and furthermore, state exactly the relative disposition of these two sections, so that the parts may be properly correlated.

In making a pattern set of this nature it is to be understood that the indications 20, insignia 21, reference characters 24 and the sets of instructions 25, 26 and 27 are all preferably printed, and the pattern set is conveniently accompanied by an instruction-

sheet 28 of the nature shown in Fig. 6. This instruction-sheet preferably shows the most economical manner of laying out the pattern sections on different lengths and widths 5 of material, as has been indicated at 29. Furthermore, the instruction-sheet conveniently shows all of the various pattern sections as at 30, and indicates—as, for example, by dotted lines 31—the various 10 groups of perforations 23 or other indicia which may be used in lieu thereof. A full explanation of these markings may be given on the instruction-sheet as at 32, it being noted that this explanation refers particularly 15 to such sets of instructions as have been indicated at 26, which latter, it will be noted, in turn refer to the instruction-sheet for detailed explanation.

The instruction-sheet also preferably has 20 a column 33 devoted to the various steps involved in cutting and assembling the garment portions, and this column may also include illustrations 34 of the finished garment, as well as a compilation 35 of the various sections included in the pattern set.

In this connection it is of particular interest to note that the identifying marks 20 applied to each of the pattern sections are conveniently included in proper order in 30 this compilation. Obviously, it is unnecessary to provide more than one pattern section for duplicate garment portions when it is merely necessary to reverse either the material or a pattern section in order to obtain 35 the opposite garment portion. With this in mind the pattern set of the present invention conveniently includes merely one complete set of sections, and in this connection it will be seen that in order to avoid 40 confusion the indications 20 each embrace a designation which specifically identifies that particular garment portion which will be provided when the section is placed face upwards upon the material to be cut. In 45 line with this procedure the illustration 34 of the finished garment has the particular garment portions which are primarily provided by the use of the pattern sections not alone identified by the characters utilized 50 at 20 and 35, but also preferably identified by shading or otherwise distinctively marking as at 37 the illustration of those portions of the garment which are initially provided by the use of the pattern set.

55 As an additional precaution against the improper use of the pattern, and even conceding that a person fails to refer to the instruction-sheet, it will be noted—particular reference being had to pattern section 11—that this section may present a compilation 60 of all of the pattern sections which are included in the set.

65 In using a pattern having the characteristics of the present invention an operator will have before her a set of pattern sections as

has, for example, been illustrated in Fig. 1. Accompanying this set will be the instruction-sheet which will show the finished parts of the garment, and will also indicate exactly those garment portions which will be formed if the pattern sections are arranged face up on the material. In this connection, as an additional precaution, or as a primary indication—assuming that no instruction-sheet is utilized—the indication 20 will show 70 exactly which garment portion will be formed with the pattern section arranged upon the material in a certain manner. The instruction-sheet will also serve as a check which will indicate exactly the number of sections which provide the finished pattern set, and in the event that the information indicated at 36 is provided on the face of one or more of the pattern sections, an operator will not 75 find it necessary to refer to the instruction-sheet for this information.

The instruction-sheet, in addition to serving as a guide in order to indicate the most economical distribution of the pattern sections upon a given size of the material, will, if desired, include information explaining 80 in detail the mode of assembly of the sections, as well as the correlation thereof and the individual manipulations to which each section may be subjected in order to produce 85 different results.

90 Furthermore, it will be noted that independent of the instruction-sheet, each pattern set will contain information which will serve to intelligently guide any person who may use the same. Thus, for example, the instruction-indicia will be clear-cut and will not alone refer to the manipulations to which the individual pattern piece or section is to be subjected, but will also preferably positively identify the next adjacent section in 95 such a manner that no error can possibly occur. Due to the explicit nature of these instructions an operator will also know, in addition to the fact that a certain section 100 is to be placed adjacent the section upon which she is working, exactly how the garment portions cut by the use thereof are to be correlated; and it will be observed that in addition to all the foregoing, if—as has 105 been illustrated—the characteristics of this invention are incorporated in a pattern set which is cut to size, i. e., the outline of which corresponds exactly to the outline of the 110 finished garment portion, a set of perfect garment portions will be provided by the expenditure of a minimum amount of effort.

115 Finally, referring to the indicia, including the notches, perforations, characters, instructions, identification marks and phrases, etc., etc., it will be noted that the form, as well as the character of all of these may readily be changed, and thus, since these and other changes may be made in the above article 120 and different embodiments of the invention 125 130

could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A pattern set, including a plurality of separate pattern sections having cut edges to be followed in cutting a finished garment portion and being provided with printed indicia at points adjacent which the garment portions are to be matched, the indicia upon different sections being of a similar character and referring to that section which is to be placed adjacent the same.

2. A pattern set, including a plurality of separate sections to be used for providing a plurality of similar garment portions and being provided with printed indicia at positions corresponding to the matchable points of the garment portions, certain of the indicia referring to sections which are to be arranged adjacent the same whereby to provide a guide in assembling the garment portions.

3. A pattern set, including a plurality of sections having cut margins to be followed in providing similar garment portions and being provided with printed indicia at positions corresponding to the matchable points of the garment portions, certain of the indicia referring to sections which are to be arranged adjacent the same whereby to provide a guide in assembling the garment portions, the indicia on different and adjacent sections at points which are to be matched being of a similar character.

4. A pattern set, including, in combination, a plurality of tissue paper pattern sections and an instruction-sheet, said sections presenting printed indicia, certain of said indicia referring to adjacent sections, and other indicia referring to said instruction-sheet.

5. A pattern set, including, in combination, a plurality of pattern sections and an instruction-sheet having an illustration of the finished garment to be provided by the use thereof, a single one of said pattern sections being adapted to be used to provide one garment portion and also a similar garment portion, those portions of the finished garment which are first provided by the pattern section being distinctively marked in the finished illustration.

6. A pattern set, including, in combination, a plurality of tissue paper pattern sections, having cut margins to be followed in providing corresponding garment portions certain of said sections being adapted to be utilized to provide more than one finished garment portion and having printed indicia applied to their bodies to indicate that particular garment portion which will be provided by the use of the corresponding pattern section when the latter is applied in a certain manner to the garment material.

7. A pattern set, including, in combination, a plurality of tissue paper pattern sections, certain of said sections being adapted to be utilized to provide more than one finished garment portion, and having printed indicia to indicate that particular garment portion which will be provided by the use of the corresponding pattern section when the latter is applied in a certain manner to the garment material, and an instruction-sheet accompanying said pattern set and bearing an illustration of the finished garment to be provided thereby, those garment portions which are primarily represented by the pattern sections being distinctively indicated in the said illustration.

8. A tissue paper pattern set having cut margins to be followed in providing corresponding garment portions, said sections including a plurality of pattern sections, each having indicia adapted to be matched with indicia on other sections, and being provided with printed instructions at points adjacent said indicia, the instructions on each section referring to another section the indicia of which is to be matched with the indicia of the section to which the instructions are applied, whereby to act as a guide in assembling garment portions provided by the use of various sections.

9. A pattern set, including, in combination, a plurality of tissue paper pattern sections having cut margins to be followed in providing corresponding garment portions of a garment, reference characters applied to said pattern sections at points corresponding to the points which are to be matched on the garment portions, and being provided with printed instructions adjacent said characters and indicating the matchable character of an adjacent section.

10. A pattern set, including, in combination, a plurality of tissue paper pattern sections having cut margins to be followed in providing corresponding garment portions, the adjacent garment portions being adapted to be joined together, said sections having their bodies provided with similar reference characters at points corresponding to the points which are to be matched on the garment portions, and being further provided with reciprocal and printed instructions adjacent said characters and indicat-

- ing the matchable character of an adjacent section.
11. A garment pattern, including a tissue paper sheet having cut margins to be followed in providing a corresponding garment portion and being provided with printed instructions adjacent the points to be matched in the garment portion and serving to indicate this function.
- 10 12. A garment pattern, including a tissue paper sheet having cut margins to be followed in providing a finished garment portion, the pattern sheet being provided with indicia at points adjacent the parts of the garment portion which are to be matched, and being further provided with printed instructions indicative of such matching.
- 20 13. A garment pattern, including a tissue paper sheet having cut margins to be followed in providing a finished garment portion, the pattern sheet being provided with two sets of similar indicia adjacent two points of the garment portion which are to be matched, said pattern being further provided with printed instructions indicative of such matching.
- 25 14. A garment pattern, including a tissue

paper sheet having a cut margin to be followed in providing a finished garment portion, the pattern sheet being provided with indicia at points adjacent the parts of the garment portion which are to be matched, and being further provided with printed instructions indicative of such matching, an instruction-sheet accompanying said pattern, and further printed instructions carried by said pattern and referring to the instructions of said sheet.

30 15. A pattern set, including a plurality of pattern sections, an identifying mark applied to each of said sections, and a compilation of the individual sections of said set appearing upon one of said sections.

35 16. A pattern set, including, in combination, a plurality of pattern sections and an instruction-sheet, each of said sections having printed instructions and printed and distinguishing identifying marks, said instruction-sheet presenting a compilation of the identifying means for all of said sections.

40 In testimony whereof I affix my signature.

45 MAX HERZBERG.

Certificate of Correction.

It is hereby certified that in Letters Patent No. 1,560,688, granted November 10, 1925, upon the application of Max Herzberg, of New York, N. Y., for an improvement in "Patterns and Pattern Sets," an error appears in the printed specification requiring correction as follows: Page 3, claim 8, strike out present lines 94, 95, 96 and 97, and insert the following instead: "*A pattern set, including a plurality of tissue paper pattern sections having cut margins to be followed in providing corresponding garment portions, said sections each;* and that the said Letters Patent should be read with this correction therein that the same may conform to the record of the case in the Patent Office.

Signed and sealed this 15th day of December, A. D. 1925.

[SEAL.]

WM. A. KINNAN,
Acting Commissioner of Patents.
